(57) CLAIM

The ornamental design for a cosmetic article basket and mirror, as shown and described.

DESCRIPTION

FIG. 1 is a front perspective view of a cosmetic article basket and mirror according to the present invention, showing in phantom cosmetic articles carried therein.

FIG. 2 is a front elevation view thereof.

FIG. 3 is a left side elevation view thereof, the right side elevation view being a mirror image thereof.

FIG. 4 is a rear elevation view thereof.

FIG. 5 is an upper plan view thereof; and,

FIG. 6 is a lower plan view thereof.

The phantom line environmental showing is for illustrative purposes only and forms no part of the claimed design.
